(57) **CLAIM**

I claim the ornamental design for a body brush, as shown and described.

DESCRIPTION

FIG. 1 is a front perspective view of the body brush, according to the present invention;

FIG. 2 is a top plan view of the body brush of FIG. 1;
FIG. 3 is a side plan view of the body brush of FIG. 1;
FIG. 4 has been amended to include the bristles at the bottom of the drawing; and,

FIG. 5 has been amended to depict that the bristles overlay the strap.
